(57) **CLAIM**

The ornamental design for a jewelry clasp, as shown and described.

DESCRIPTION

FIG. 1 is a perspective view of a jewelry clasp;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a perspective view thereof showing the jewelry clasp in use.

The broken lines shown in the drawing views are included for the purpose of showing environmental structure that forms no part of the claimed design.
